UNITED STATES PATENT OFFICE.

KARL TORSTEN FREDRIK JUNG, OF KALMAR, SWEDEN.

METAL PLANER.

Application filed November 8, 1918. Serial No. 261,698.

To all whom it may concern:

Be it known that I, KARL TORSTEN FREDRIK JUNG, a subject of the King of Sweden, and resident of Kalmar, Sweden, have invented certain new and useful Improvements in Metal Planers (for which I have filed an application in Sweden, May 9, 1917), of which the following is a specification.

In the rapid progress of machine-tools in general, as a result of the introduction of the modern high-speed tool steel, the planers have been left far behind. In recent tables of cutting speeds the working speed for turning is stated as 18 to 36 meters per minute, but for planing as only 8 to 15 meters per minute. If we furthermore consider, on the one hand, the useless return-stroke, which although taking place with a speed 2 to 4 times the cutting speed, represents a considerable loss in effective cutting speed, and on the other hand the power which is spent in accelerating the reciprocating masses of table and work-piece, it is no wonder that the planer is considered in many modern workshops as a rather antiquated type of machine.

The reason for keeping the cutting and return speeds so low is the reciprocating movement of the table, the change between the constant cutting speed and the constant but greater return speed taking place abruptly (almost instantaneously). The cutting tool consequently will hit the work-piece with a shock, which if the cutting speed should exceed the above stated maximum cannot be sustained, neither by the tool nor the work-piece, especially when the latter consists of cast material. Also the return speed has to be kept within the limits given above on account of the great kinetic energy which has to be taken up and to be delivered almost instantaneously at the dead points.

Attempts have been made to increase in some degree the power of planers by giving the table two or more cutting speeds, the smaller being coupled in at the dead point, the greater after the tool has entered the work-piece, the smaller being coupled in again before the end of the cut. By these means each of the shocks at the beginning and end of the cutting stroke will be di-

vided in two (or more) smaller shocks, other inconveniences remaining.

The present invention relates to means for so controlling the speed of the table, that during a double stroke A—D—A (see Figs. 1, 3, 6) of the table, the speed during a certain period A—B in the beginning of the cutting stroke continually increases from 0 or a small speed (V min) to the normal cutting speed and then during a corresponding period C—D at the end of the stroke again continually decreases to 0 (resp. v min). During the return stroke which takes place with a greater speed, corresponding continuous speed-variations $0 (v^1 \text{ min}) — v^1 — 0 (v^1 \text{ min})$ take place. The length of stroke, A D, is, as generally known, effected by means of a suitable reversing mechanism, actuated by tappers or dogs on the table.

By the mentioned continuous speed-variations the tool enters the work in the vicinity of point A with a very small speed and consequently without any shock or blow. The velocity then continuously increases to point B, where the constant cutting speed starts. Immediately before point D the tool leaves the work without shock. By these means the cutting speed is limited only by the strength of the tool and may be as high as in modern high speed lathes. When a number of work pieces are mounted on the table similar speed-variations may, according to certain constructional forms of the invention, be effected at points corresponding to the said different work-pieces.

As the return stroke has similar acceleration and retardation periods D E, F A at the beginning, and end, instead of the indetermined and almost instantaneous reversal by means of belt-shifting mechanism or similar, and as furthermore the speed curve during these periods may be chosen so as to keep the accelerating forces constant or variable with a comparatively low maximum value, the return speed may also be increased to a multiple of the usual, while keeping the said maximum value of the accelerating forces below the values in corresponding usual planers.

For a fuller understanding of the invention reference is had to the accompanying drawings in which Figs. 1, 6 and 20 are

speed diagrams of a complete cycle of reciprocating movement in planer construction, embodying different forms of the invention;

Fig. 2 is sectional plan view taken through the bed driving shafts;

Fig. 3 is a diagrammatic view of a detail;

Fig. 4 is a side elevation; and

Fig. 5 is a cross section on the line A—B—10 C—D in Fig. 4,

Fig. 7 is a sectional plan view, taken on a line through the bed driving shafts;

Fig. 8 is a vertical longitudinal section through the machine;

Fig. 9 is a vertical section through the middle of the machine;

Fig. 10 is a horizontal section on the line A—B—C—D in Fig. 11;

Fig. 11 is a side elevation the lower part 20 thereof being a section on the line E—F in Fig. 7; and

Figs. 12—19 are diagrammatic illustrations of the table actuating mechanism in four different positions.

Figs. 21—24 show in horizontal section, cross section of a detail, side view, and longitudinal section respectively, a construction, pertaining to Fig. 20. Fig. 23^a shows the dogs 20' and 21' in Fig. 23 in plan view.

In the constructional form shown in Figs. 2—5, 1 is the driving pulley, the movement of which is transmitted by the pinion 3, and spur gear 4 to the shaft 15, connected with the shaft 16 through either one of the pairs 35 of gears 5, 6 or 7, 8. All these gears are loosely mounted on their shafts. By means of the coupling K either gears 5 and 6 or 7 and 8 of these gears are coupled to the shafts 15, and 16, respectively. The gears 5 and 6 40 are two elliptical gears and therefore change the constant angular velocity of the shaft 15 to a variable angular velocity of the shaft 16. The gears 7, 8 are two ordinary spur gears and transmit to the shaft 16 rotary motion, the angular velocity of which equals the maximum value of the angular velocity transferred to the shaft 16 by the elliptical gears 5 and 6 (position II, Fig. 3). The movement of the shaft 16 is transmitted by 45 means of the pinion 9 and spur gears 10, 11 to two shafts 17, 18, on which are keyed two spur gears 12, 13 gearing with the usual rack 14 on the under side of the table. The gears 9, 12, 13 are fixed on their respective shafts, 50 but the gears 10 and 11 are loosely mounted on their shafts. The coupling K¹ in the position I connects the gear 10 to the shaft 17 and the driving gear 12, which therefore moves the table in the direction shown by 55 the arrow c, corresponding to the cutting stroke. In the position II the coupling K¹ connects the gear 11 to the shaft 18 and the gear 13, which moves the table in direction 60 of the arrow d, corresponding to the return stroke. The return speed is considerably

in excess of the cutting speed, as is seen by the proportion between the diameters of the gears 10 and 11.

To bring into action the mechanism for acceleration, retardation and reversal of the table, two movable dogs 19, 20 are slidably 70 fixed to the table. The shorter tongues of

said dogs are acting on the mechanism which brings the coupling K and the elliptical gear 75 in action, and the longer tongues act on the mechanism, which brings into action the coupling K¹ to effect the reversal of the table.

Each of the shorter tongues acts on the working face of one of the two-armed levers 21, 22, the lower arms of which form 80

cog-sectors co-acting with the spur-wheels 24, 23 of which the latter meshes with a spur-wheel 25, attached to the same shaft as the wheel 24, thus coupling the two levers 21, 22

together and causing them to swing in opposite directions. The rack 26 gears with 85

the wheels 24, 27, the latter of which is attached to a shaft 28, the end of which is threaded and has a nut 29 acting on the lever

30, which moves the double coupling K in 90 the one direction or the other. The elliptical wheel 6 is connected to a wheel 32 gearing with a wheel 33 of equal diameter on the

shaft 34, underneath the shaft 16. On the other end the shaft 34 carries a circular disc 95

35 having a slot 48, in which the roller 36 on the free end of the single-armed lever 37

can fall in, in a certain position (II, Fig. 3) of the elliptical wheel 6 or of the disc 35, which make one revolution simultaneously. 100

The lever 37 has, opposite to the roller 36, a small pin 38, which locks the rack 26, when

entering a slot therein. When the roller 36 falls into the slot a the pin 38 passes out of

the slot in the rack 26, thereby releasing the 105

latter, which will move under the action of the spring 39 to its right end position, cor-

responding to position II of the coupling K, thus uncoupling the elliptical gear 5, 6 and 110

coupling in the ordinary spur gear 7, 8.

To reverse the motion of the table by means of the double coupling K¹ the cou-

pling lever 47 has a third arm 46 which is moved in the one direction or the other by

means of the reversing anchor 40, the link 115

41, the lever 43, the shaft 44, the arm 45 and the link 42.

Fig. 1 represents the speed-diagram of 120

this mechanism. A D represents the stroke of the machine. The cutting speed v is plotted upwards and the return speed v'

downwards. The speed-curve during a double stroke of the table is therefore represented

by the lines A B¹ C¹ D E¹ F¹ A. When the

table reaches the position A and is going to 125

start the cutting work stroke, the longer

tongue of the dog 20 has hit the left work-

ing face of the reversing anchor 40, which

at this line is in its uppermost position and

has forced said face down in the position 130

shown in Fig. 3, thus bringing the coupling K^1 from position II to position I in which it remains during the whole cutting stroke. The coupling K is at the start of the cutting stroke in the position I, the movement, therefore, being transmitted by the elliptical wheels 5, 6, which during the last part FA of the return stroke have made half a revolution and are at this moment in position I, 5 Fig. 3. While the gear 5 makes half a revolution from the position I to the position II, the slide moves from A to B with a continuously increased speed. At the point B it has reached its full cutting speed v . During 10 the way F—A—B the elliptical gear 5, 6 and consequently also the disc 35 has made exactly one revolution, and the slot now reaches the roller 36 and is engaged thereby thus releasing the rack 26, which is forced by the 15 spring 39 to its right end-position, thereby uncoupling the elliptical gear 5, 6 and coupling in the ordinary gear 7, 8. The table then moves from B to C at the constant cutting speed v . At the point C the shorter 20 tongue of the dog 19 hits the working face of the lever 21 and forces it from position a to position b , thus moving the rack 26 from its right to its left end-position, and coupling the gear 7, 8 and coupling in the el- 25 liptical gear 5, 6, which starts in revolving half a revolution from position II, Fig. 2^a, to position III, causing the speed of the table to decrease continually from v to v min during the way C—D. When the disk 35 30 starts to rotate the roller 36 leaves the slot 48 and rolls on the periphery of the said disc, causing the pin 36 to fall in its slot in the rack 26, thus locking the latter in the left end-position. At the point D the longer 35 tongue of the dog 19 hits the right working face of the reversing anchor 40 and the coupling K^1 is reversed from position I to position II. The gear 13 is then brought 40 in action, the return stroke is started and the same course, as in the cutting stroke is 45 repeated, i. e. the reversals of the coupling K take place at the points E and F. The proportion between the speeds v and v_1 is determined by the diameters of the wheels 10 50 and 11. It is evident that $\frac{AB}{AF} = \frac{CD}{ED} = \frac{v}{v_1}$, as the distances AB and AF are performed in the same time (corresponding to half a revolution of the wheel 5). That the distance 55 AF and ED in the return stroke are greater than the corresponding distances AB and CD in the cutting stroke or, conversely, that FE is smaller than BC, results in a material advantage, inasmuch as the accelerating 60 forces during the return stroke will be considerably smaller, than they would be if said distances were equal and as it is said accelerating forces which limit the return speed v_1 . When for instance in the particular 65 arrangement $v_1 = 3v$, the accelerating forces

during the return stroke are only three times the same forces during the cutting stroke, while they should have been 9 times as great if AF had been equal to AB. To this advantage, however, is incident the dis- 70 advantage, that the smallest possible stroke of the machine AF+ED will be greater than otherwise. When however a smaller stroke is desired it is possible to let the planer work as a usual planer, by letting 75 the coupling K stay in position II. In this case it is however necessary to couple in the smallest speed.

The cutting steel enters and leaves the work piece at points G and H, respectively, 80 which can be located close to the end points of the stroke, said end points with the transmission of motion according to the present invention being absolutely fixed and not as in the usual planers determined by the 85 masses of table and work piece and by the elasticity of belts or resilient couplings which take up the kinetic energy. The speed with which the steel enters and leaves the work piece, respectively, may consequently 90 be brought close to v min, whereby even when cutting speeds as high as 30 to 36 meters per minute are used the shocks will be negligible.

In the constructional forms described be- 95 low v min may be reduced to 0, and the shocks furthermore lessened.

When high speeds are used, the accelerating forces nevertheless will be great. As, however, according to the present invention 100 the pulley 1 is continuously driving and its shaft therefore always rotates in the same direction, it is possible to place a fly wheel 2 on the same, taking up energy during the periods CD and AF and delivering the same 105 during the periods AB and ED. No energy will then be lost by the reciprocating movement.

Figs. 7-19 show another constructional form for the transmission of motion pertaining to Fig. 6. It differs from the form shown in Figs. 2-5 mainly in that the speed of the table decreases to 0, and that the acceleration and retardation periods AB, CD during the cutting stroke are equal or nearly 110 equal to the corresponding periods ED, FA during the return stroke. Consequently the speed, with which the steel enters and leaves the work piece, is brought down very nearly to 0. The accelerating forces during the re- 115 turn stroke become greater, but may be taken up by a fly-wheel.

1' (Fig. 7) is the driving pulley mounted on the shaft 17', which also carries the fly wheel 2' and the three spur gears 3', 5' and 125 8' which are loosely mounted thereon and may be coupled by means of the couplings K^2 , K^1 and K . The gear 3' engages directly the gear 4' attached to the shaft 18', and the gear 5' engages by means of an intermedi- 130

ate gear 6', the gear 7', attached to the same shaft 18'. The gear 8' finally engages a gear 9' on the shaft 20'. The gear 9' carries a pin 16' having movement in a slit 22' on the spur sector 10', oscillating on the shaft 21', said sector receiving a reciprocating movement when the gear 9' rotates in the direction of the arrow α , which movement is transferred to the spur gear 11' engaging the sector 10'.
 10 The spur gear 11' during one revolution of the gear 9' receives an angular velocity varying between 0 when the pin 16' is in the positions I, III. (Fig. 8) and two different maxima in the positions II, IV respectively of said pin. The former and smaller is proportional to the cutting speed v and the latter and greater to the return speed v^1 . By one of the wheels 4', 7' or 9' whichever may be at the moment in the transmission
 15 20 train the movement is transmitted by means of the spur gear 12', to the gear 14', driving the rack 15' of the table.

The transmission of motion is indicated in the table following below, in which for every one of the couplings K^2 , K^1 , K I is the position, in which the corresponding gear 3', 5' or 8' is engaged and II the position, in which the same gears are disengaged. The wheels marked with arrows in Figs. 4 and 5, 30 always move in the direction shown by these arrows, the other gears during different periods move in opposite directions.

Part of the stroke A.D.	Working wheels and their direction of rotation.	Position of the pin 16.	Position of K .	Position of K^1 .	Position of K^2 .

The mechanism for accelerating and retarding the movement of the table is also in this case brought into action in the points CF of the diagram by means of two movable dogs 23', 24', Figs. 11, 12, 14, 16, 18, on the table. The reversal of the table by means of the mechanism 16', 10', 12', will as is easily realized by the character of said mechanism, in this case follow automatically. The dogs 23', 24' are acting on the working faces 25' and 26' of the coupling anchor 27' which acts on the curve slide 28', Figs. 10, 11, in the one direction or the other by means of the link 29', the lever 30', the inner shaft 31', the lever 32', Figs. 7, 9, 10, in the opposite end of said shaft, the link 33', the single-armed lever 34' and the link 35'.
 45 50 55 60 Said curve slide 28' by means of its V-shaped curve 36' moves the roller 37', affixed on the lower side of a sliding bar 38' having square section. Fixed on the top of said bar 38' are the pins b^1 , c^1 , d^1 , e^1 , f^1 . The pins
 65 b^1 , c^1 , e^1 , are rigidly attached to the sliding

bar and the pins d^1 and f^1 are slidably arranged in their respective holes in the bar 38' and are pressed downwards against arms 39', 40', Fig. 10, by small springs, not shown. The arm 40' is fixed to the inner shaft 41' and the arm 39' is fixed to the hollow shaft 42'. At its opposite end the shaft 41' carries an arm 43', and the shaft 42' carries a similar arm 44'. Each of these arms carries a roller 45' respectively 46', Fig. 11, which is pressed as by means of a spiral spring 49' against a curve 47' or 48', respectively the elevated parts of which covering each 180° of the circumference. The curves 47', 48', Fig. 10, are rigidly connected to the spur wheel 9', also carrying two tapered dogs 50', 51' adapted to act on the roller 52' of the lever 34' at the points E. B., Fig. 6, where the accelerating mechanism 8', 9', 16', 22', 10' has to be uncoupled. The couplings K^2 , K^1 and K are brought in their active or inactive position by means of coupling levers 53', 54', 55', Figs. 11, 12, 14, 16, 18, turning on pins 56', 57', 58'. At their right ends said coupling levers carry projections adapted to cooperate with the pins b^1 , c^1 , d^1 , e^1 , f^1 , Figs. 10, 13, 15, 17, 19, of the sliding bar 38', in such a way that the pin b^1 is embraced by the projection of the lever 53' of the coupling K , and the corresponding projections of the lever arms 54', 55' of the couplings K^1 , K^2 are situated normally, the former between the pins c^1 and d^1 and the latter between the pins e^1 and f^1 .

While the table is performing its working stroke from B to C, see the diagram, Fig. 6, the various parts of the table actuating mechanism are in the position, shown in Figs. 12, 13. At the point C the dog 23' hits the working face 26' of the anchor 27' and brings it down from point T^1 to point M^1 , Figs. 11, 14, 17. By the mechanism 29', 30', 32', 33', 34', 35' the curve slide 28' is then caused to leave its middle position, Fig. 13 and is moved to its left end-position, Fig. 15. By the roller 37' the sliding bar 38' is then brought down in the position Fig. 15. The fix pins b^1 , c^1 force the coupling levers 53', 54' from the top positions, shown in Fig. 13, and moves same to the lower positions in Fig. 15, thus bringing the coupling K , Fig. 7, in action and uncoupling the coupling K^1 . As the roller 45' of the arm 43' is presently in engagement with not-elevated part of the curve 47', the slide pin f^1 is in its lower inactive position and the coupling lever 55' passes over f^1 , when the sliding bar 38' takes the position in Fig. 15. When the coupling K is thus brought into action at point C, the pin 16' is in position II and starts its rotation in the direction of the arrow α , Fig. 8. By means of the wheels 8', 9', the pin 16' working in the slit 22' of the spursector 10', and the wheels 11', 12', 14', the motion is transmitted to the table to move the latter.

from C to D at a speed which continuously decreases to 0, when the pin 16' rotates from position II to position III. When the pin is moving from position III to position IV, 5 the table starts its return stroke and goes from D to E at a speed, which increases from 0 to the normal return speed v^1 . At point E the wheel 9' and consequently also the tapered dogs 50' and 51' have made half 10 a revolution and take the positions, shown in Fig. 16. The dog 51' at this moment has hit the roller 52' and forces the lever 34' from the positions ℓ , Fig. 14, to the position j , Fig. 16, thus bringing the curve slide 15 28' back to its middle position. As the roller 46' of the arm 44' is now in the inner position and the pin d^1 is in its lower, inactive position, the slide bar 38', when brought by the curve slide 28' to its top position, Fig. 20, raises the coupling levers 53', 55' to their top positions, while leaving the lever 54' in its lower, inactive position, thus coupling K and coupling in K^2 . By means of the spur-wheels 3', 4', 12', 14' the table is then caused 25 to continue its return stroke from E to F at a constant speed v^1 . At point F the dog 24' hits the working face 25' and it will easily be seen that the different parts will take the positions shown in Figs. 18, 19 and the periods 30 of retardation FA and acceleration AB will follow when the pin 16' makes half a revolution from IV to II.

That the periods AB and CD in this case are not in the same proportion to the periods 35 AF and ED as v to v^1 as formerly but are nearly equal to one another depends obviously thereupon that the corresponding ways of the pin 16' are unequal. It is also evident that it is possible to determine the proportion 40 $\frac{AB}{AF}$ within certain limits by choosing the length of the slit 22' and its distance from the shaft 21' accordingly.

Figs. 21-24 show a third constructional 45 form of the mechanism for transmission of motion pertaining to Fig. 20 which has the advantage, that it makes it possible to give any desired form to the speed diagram, that is, the absolute value of the speeds v and v^1 50 as well as the form of the speed curve may be arbitrarily determined by placing dogs of corresponding form and position on the table. Fig. 20 shows a suitable form of the speed curve, a modification of the same being shown by the dot and dash lines.

1" is the driving pulley, the shaft 25" of which also carries the fly wheel 2" and the pinion 3" which meshes with a gear 4", attached to the shaft 26". The gear 4" is connected to another smaller gear 6", which constitutes the inner gear in a planetary gear arrangement 5", 6", 7", 8", the outer gear 5" of which, by means of an outer cog rim, drives the gears 29" and 30" on the 60 shafts 27", 28" carrying also the gears 23", 24", gearing with the rack 31" of the table. The gear 23" drives the table during the cutting stroke AD, the gear 24" during the return stroke DA, according as the coupling K is in the position I or II. The planetary gears 7", 8" rotate on pins 9", 10", attached to a disc 11" which loosely rotates about the shaft 26" and is fixed to the worm gear 12". This worm gear 12" gears with the worm 75 13" on the shaft 35" as which by means of a spur gear drives a friction disc 14", the working surface of which is parallel to the shaft 25". Another friction disc 16" is slidably mounted on this shaft and can, by means of a suitable coupling lever 17" (Fig. 80 23), be moved in radial direction over the disc 14". 15" is another friction disc, which is held against the disc 16" by means of a spring.

When the disc 16" is moved to inoperative position relatively to the disc 14", and the latter therefore comes to rest, the gears 12", 11" and the pins 9", 10" also will come to rest. Through the gears 3", 4" and 6" and the planetary wheels 7", 8" rotary motion of shaft 25" will be transmitted in the direction given by the arrows to the gear 5", which will then rotate in the direction of the arrow a (Fig. 24) with a certain speed. In reality, however, the disk 95 16" under the influence of suitable dogs on the table will successively assume positions marked I to III and intermediate positions on the friction disc 14". When the disc 16" is in one of these positions it will cause the 100 disc 14" to rotate in the direction corresponding to the direction of rotation of the disc 16" indicated by the arrow (Fig. 24). Through the worm 13" this rotation is transmitted to the worm gear 12" and to 105 the disc 11" and the pins 9", 10", which are then caused to rotate in the direction of the arrow b (Fig. 24) imparting a corresponding rotation to the gears 7", 8". The nearer the disc 16" is brought to the 110 centre of the disc 14", the more rapidly the disc 14" and therefore also the pins 9", 10" will rotate. The angular velocity of outer wheel 5" then decreases in such a manner that for instance the position I of 115 the disc 16" corresponds to the return speed v^1 of the table, the position II to the working speed v and the position III to the speed 0 of the same. It is therefore obvious that by giving the working surfaces 120 of the dogs a suitable height, the value of the speeds v and v^1 may be varied, and that by choosing a suitable length and form of these working surfaces, it is possible to determine arbitrarily the length of the acceleration and retardation periods as also the form of the speed curve during these periods, as is shown by the full line curve and the dash and dot curve parts AB' and AB², respectively, in Fig. 20. By placing 125 130

extra dogs on the table between the ordinary ones, it is possible to afford during the stroke such variations of the speed as indicated by the dot and dash curve part *d* 5 (Fig. 20). In this way it is possible to cut with great speed even such work pieces which have two or more different surfaces in the same plane, without danger of breakage of working tool or material when the 10 tool enters or leaves the work piece.

The work of the machine during a double stroke of the table is illustrated by the following table.

15	Part of the stroke AD.	Position resp. movement of the wheel 16.	Position of the coupling K.
20	A-B.....	III-II	I
	B-C.....	II	I
	C-D.....	II-III	I
	D-E.....	III-I	II
	E-F.....	I	II
	F-A.....	I-III	II

25 The mechanism for acceleration, retardation and reversal of the table is actuated by two movable dogs 20", 21" on the table. Said dogs on their lower surface form guide-ways for governing the roller 32" moving by means of the lever 33", the shaft 34", the lever 36", the link 37" and the lever 17" the friction disc 16" between its different positions I to III. The ways for the roller 32" are formed on the one side by the vertical walls of the V-shaped grooves in the dogs 20", 21" on the other side of the tongues 38", 39", which turn on pins 40" 41" and are kept by springs, not shown, in the positions shown in Fig. 23.

40 The mechanism for reversing the table, 45 consists of the usual reversing anchor 42", which, as is easily realized, is actuated at the end points A and D by the tongues 43", 44" on the dogs 20", 21". The reversing anchor is fixed to the inner shaft 45", which by means of the lever 46", the link 47" and the three armed lever 48" actuates the coupling K.

When the table performs its stroke from 50 B to C, Fig. 20, the coupling K is in position I, and the disc 16" in position II, as indicated in Fig. 21. The roller 32" has a corresponding position on the line B" C", Fig. 23. When the table reaches the 55 point C, the point C" of the dog 20" reaches the roller 32". When the table moves from C to D the roller 32" slides from C" to D", pressing down the tongue 38" by means of the mechanism 33", 34", 36", 37", 17" to move the disc 16" from position II to 60 position III. At point D the tongue 43" hits the right working face of the reversing anchor 42" and brings the coupling K from position I to position II, thus reversing 65 the table. When the table then is moving

from D to E the roller 32" passes from D" to E" and moves the disc 16" from position III to position I, accelerating the table from the speed 0 to the normal return speed v^1 . At the other end of the stroke the same 70 action is repeated under the control of the dog 21.

It is obvious that in this constructional form, it is possible to omit the gears 24", 30" and effect the reversal by causing the 75 friction wheel 16" to act on different sides of the centre of friction disc 14" during the cutting and return strokes. This would, however, require a considerably increased 80 power, as the pressure between the thread of the worm 13" and the cogs of worm gear 12" in this case would counteract the movement.

It is obvious that the invention is not limited to the constructional forms shown. 85

I claim:

1. In a planer, the combination with a table and the planing tool, one of which is movable, of a constantly rotating driving shaft, another shaft, means for changing the 90 constant rotation of said driving shaft to a variable rotation of said other shaft, and means to impart from said other shaft and to the movable member of the planer a substantially uniform motion during the 95 greater part of the cutting stroke and a retarding motion during a relatively small part of the cutting stroke at the end thereof.

2. In a planer, the combination with a table and the planing tool, one of which is movable, of a constantly rotating driving shaft, another shaft, means for changing the constant rotation of said driving shaft to a variable rotation of said other shaft, and means to impart from said other shaft and 100 to the movable member of the planer an accelerating motion at the beginning of the cutting stroke during a relatively small part thereof and a substantially uniform motion during the greater part of the stroke. 105

3. In a planer, the combination with a table and the planing tool, one of which is movable, of a constantly rotating driving shaft, another shaft, means to change the constant rotation of said driving shaft to a 110 variable rotation of the said other shaft, and means to impart from the said other shaft and to the movable member of the planer an accelerating motion at the beginning of the cutting stroke during a relatively small part thereof, a substantially uniform motion during the greater part of the cutting stroke, and a retarding motion during a relatively small part of the cutting stroke at the end thereof. 115

4. In a planer, the combination with a table and the planing tool, one of which is movable, of a constantly rotating driving shaft, another shaft, means to change the constant rotation of said driving shaft to a 120

- variable rotation of the said other shaft, and means to impart from the said other shaft and to the movable member of the planer during the cutting stroke and the 5 return stroke an accelerating motion, a substantially uniform motion and a retarding motion, the rate of motion during the return stroke being greater than during the cutting stroke.
- 10 5. In a planer, the combination with a table and the planing tool, one of which is movable, of means operative to impart to the movable member during the cutting stroke and the return stroke an accelerating 15 motion, a substantially uniform motion and a retarding motion, said means being so constructed and arranged that the periods of acceleration and retardation during the return stroke are greater than during the cutting stroke.
- 20 20. In a planer, the combination with a table and the planing tool having relative reciprocating movement, of means operative to continuously increase the speed through a fixed distance at the beginning and continuously decrease the speed through a fixed distance at the end of each stroke, means for temporarily decreasing and then again increasing the speed during the cutting stroke, and means for maintaining a substantially constant speed between the periods of acceleration and retardation, said means being operative to give a greater speed during the return stroke than during the cutting stroke.
- 25 6. In a planer, the combination with the table and the planing tool having relative reciprocating movement, of a constantly rotating driving shaft, means for transmitting from said shaft and to the movable member 30 of the planer a movement gradually accelerated from a low value to a maximum value through a fixed distance at the beginning of each stroke and gradually retarded from said maximum value to a low value through 35 a fixed distance at the end of the stroke, said means being constructed and arranged to accelerate the speed during the return stroke to a greater maximum value than during the cutting stroke.
- 40 7. In a planer, the combination with the table and the planing tool having relative reciprocating movement, of a constantly rotating driving shaft, means for transmitting from said driving shaft and to the movable 45 member of the planer a movement continuously accelerated from a low value to a maximum value through a fixed distance at the beginning of each stroke and continuously retarded from said maximum value to a low value through 50 a fixed distance at the end of the stroke, said means being operative to accelerate the speed during the return stroke to a greater maximum value than during the cutting stroke, and means 55 for maintaining substantially constant speeds between the periods of acceleration and retardation.
8. In a planer, the combination with the table and the planing tool having relative 60 reciprocating movement, of means operative to make the return speed greater than the cutting speed, and means for gradually increasing the speed through a fixed distance at the beginning and decreasing the speed through a fixed distance at the end of each stroke, said means being operative in such manner that the distances through which the acceleration and retardation take place are greater during the return stroke than during the cutting stroke.
9. In a planer, the combination with the table and the planing tool having relative reciprocating movement, of means operative to continuously increase the speed through a fixed distance at the beginning and continuously decrease the speed through a fixed distance at the end of each stroke, means for temporarily decreasing and then again increasing the speed during the cutting stroke, and means for maintaining a substantially constant speed between the periods of acceleration and retardation, said means being operative to give a greater speed during the return stroke than during the cutting stroke.
10. In a planer, the combination with the table and the planing tool having relative reciprocating movement, of a constantly rotating driving shaft, means for transmitting from said shaft and to the movable member 90 of the planer a movement gradually retarded from a maximum value to zero through a fixed distance at the end of each stroke and again gradually accelerated from zero to another maximum value through a 95 fixed distance at the beginning of the following stroke, and means for maintaining a substantially constant speed between the period of acceleration and retardation, said means being operative to give greater speed 100 during the return stroke than during the cutting stroke.
11. In a planer, the combination with the table and the planing tool having relative reciprocating movement, of means for gradually increasing the speed from a low value to a maximum value through a fixed distance at the beginning of each stroke and for gradually decreasing the speed from said maximum to a low value through a fixed 110 distance at the end of the stroke, said means being operative to accelerate the speed to a greater maximum value and through a greater distance during the return stroke than during the cutting stroke.
